UNITED STATES PATENT OFFICE.

FREDRICK D. McGINLEY, OF PLEASANT BEACH, AND JOSEPH J. MICHELS, OF SYRACUSE,
NEW YORK.

AUTOMATIC SIGNAL FOR RAILWAY-CROSSINGS.

1,254,250.

Specification of Letters Patent. Patented Jan. 22, 1918.

Application filed December 26, 1916. Serial No. 139,036.

To all whom it may concern:

Be it known that we, FREDRICK D. McGINLEY and JOSEPH J. MICHELS, citizens of the United States of America, and residents 5 of Pleasant Beach and Syracuse, respectively, in the county of Onondaga, in the State of New York, have invented new and useful Improvements in Automatic Signals for Railway-Crossings, of which the following, taken in connection with the accompanying drawings, is a full, clear, and exact description.

This invention relates to certain improvements in automatic signals for railway crossings and involves the use of one or more car-operated semaphores mounted upon a suitable tower or towers at one or both sides of the track near the crossing for the purpose of warning vehicle drivers and pedestrians 20 of the danger of an approaching train or car along the track.

One of the objects of our present invention is to provide the signal-operating means with one or more primary actuating devices 25 located some distance to one side, or as the object approaches to the crossing and in proximity to one or the other of the rails of the track, to be operated by the flange of the wheel of the first approaching car for shifting the semaphore from its normally concealed or partially concealed position to its warning position.

Another object is to provide this signal-operating mechanism with automatic means 35 for locking the signal in its warning position until the approaching car or train reaches the crossing, and incidentally for locking said operating mechanism in its shifted position during the same period.

40 A further object is to provide suitable means for providing a primary restoring device located at or near the crossing adjacent one of the rails of the track to be operated by the wheel-flange of the foremost car for 45 releasing the locking means and restoring the signal and its operating means to normal position.

A still further object is to prevent a repetition of the operation of the semaphore to 50 its warning position in case a train is of sufficient length to span the distance between the primary operating device and primary restoring device.

Other objects and uses relating to specific parts of the apparatus will be brought out 55 in the following description.

In the drawings—

Figure 1 is a perspective view of a portion of a railway track and highway crossing, together with the signal towers, the signals and their operating mechanisms being 60 in their normal positions for a clear track and safe crossing.

Fig. 2 is an enlarged longitudinal vertical sectional view, partly broken away, 65 along the track through one of the signal towers, showing portions of the signal-operating mechanism, and also showing in section the sub-surface housings for portions of said mechanisms at the opposite approaches 70 to the crossing.

Fig. 3 is a vertical sectional view taken in the plane of line 3—3, Fig. 2.

Fig. 4 is a transverse vertical sectional view through the towers at opposite sides of 75 the track, showing the latter in section, and the housing for one of the primary signal-setting devices in elevation.

Fig. 5 is an enlarged transverse vertical sectional view, partly broken away, through 80 one of the housings for the primary signal-setting device, and a portion of the housing for the corresponding part of the signal-operating mechanism.

Fig. 6 is a side elevation of the housing 85 shown at the right of Fig. 5, and the primary signal-setting device therein.

Fig. 7 is a horizontal sectional view through the base of one of the signal towers and the housing for the primary signal-restoring device, together with the housings 90 for one of the primary signal-setting devices and corresponding portion of the signal-operating mechanism.

Fig. 8 is a vertical sectional view through 95 the housing for one of the primary signal-restoring devices.

Fig. 9 is a side elevation, partly broken away, of the same housing and adjacent portions of the signal-restoring device. 100

In order that my invention may be clearly understood, I have shown a portion of a railway track —A— and a highway crossing —B—, near which is located at opposite sides of the track a pair of signal towers 105 —1— of similar construction having their

bases properly secured in the ground beneath the surface thereof, said towers and bases being hollow for receiving the adjacent portion of the signals and operating mechanisms therefor.

5 The upper portion of each tower contains a pair of distinctive signaling devices consisting, in this instance, of semaphore arms —2— and —2'— which are pivotally mounted side by side upon a pivotal bolt —3— to swing vertically about the same axis from a substantially vertical position within the upright portion of the tower to a substantially horizontal position within a lateral extension —1'— leading from one side of the upper portion of the tower in the direction of length of the track, and preferably toward the crossing —B—.

10 The semaphores —2— and —2'— preferably consist of flat sheet metal blades having distinctive markings, such as apertured letters "Go" and "Stop," which are visible through openings —4— in the outer sides of the extensions —1'— opposite those which 15 face the track so as to be readily visible to approaching pedestrians or drivers of vehicles.

15 A suitable lamp, such as an incandescent electric lamp, —5— and a reflector —6— are placed within each extension —1'— directly 20 behind the active semaphore so as to project a strong reflected light through the apertured letters and thence through the sight opening —4— to enable the signal to be readily seen at night, the semaphore blades —2— and —2'— being provided with 25 suitable means for receiving and retaining distinctive colored (as red and green) glass plates —7— to further distinguish one signal 30 from the other, the red glass being usually placed in the "Stop" signal and the green glass in the "Go" signal.

35 The lower portions of the extensions —1'— and adjacent sides of the upright portions 40 of the towers are slotted at —8— to permit the free operation of the semaphore blades therethrough, each blade being counterbalanced by a suitable weight —9— to enable 45 it to be operated more easily in a manner 50 hereinafter described.

Signal-setting means.

55 Like semaphores of both towers are adapted to be set simultaneously by the advance car of a train approaching the crossing from either direction, and for this purpose is provided with a pair of primary operating devices consisting of depressible levers, or more properly, lever-plungers —10— located at opposite approaches to or some distance from opposite sides of the highway —B—, usually a distance somewhat greater than the maximum length of freight train so as to cause the operation of the danger 60 signal at a safe time before the train or car 65

reaches the crossing, the upper ends of the lever-plungers —10— being disposed in close proximity to the inner face and normally slightly above the top of one of the rails of the track —A— to be engaged and 70 first rocked and then depressed by the flange of the first approaching car-wheel of the train or car.

75 The lower end of each lever-plunger —10— is weighted to restore the lever to an upright position and is guided in a vertical way —11— in one side of a housing —12— which is embedded in the ground beneath the surface thereof just inside of the rail, as shown more clearly in Fig. 5, and 80 contains a bell-crank lever —13— fulcrumed therein and constituting a part of the signal-operating mechanism.

85 The intermediate portion of the lever-plunger —10— is pivotally mounted upon a stud or bearing —13'— having one end pivoted at —14— to one of the arms of the bell-crank lever —13— and its other end provided with a roller bearing —15— riding in a vertical slot —16— in the adjacent side 90 of the guideway —11— of the housing —12—, but wholly below the top of the housing where it is protected from the elements.

95 The guideway —11— and slot —16— are of sufficient vertical length to allow the lever-plunger —10— to be depressed as far as possible by the flange of the car-wheel, thereby depressing the bearing —13'— and adjacent arm of the bell-crank lever —13—, and for the purpose of throwing the danger 100 signal from its normal position into registration with the sight opening —4— and simultaneously restoring the safety signal to its normal position in a manner herein-after more fully described.

105 The free end of the bell-crank lever —13— which is pivotally connected to the bearing —13'— extends a sufficient distance beyond the pivot —14— and under said bearing to normally hold the latter against 110 the upper end of the opening in the lever-plunger —10— through which the bearing extends, but it will be observed upon reference to Fig. 5 that this opening, as —10'—, is slightly elongated vertically, the object 115 of which is to permit a continued downward movement of the pivoted end of the bearing —13'— and bell-crank lever —13— in case the flange of the car-wheel should continue to depress said lever-plunger after the roller 120 bearing —15— engages the lower end of the slot —16—, under which conditions, the bearing —13'— would simply rock about the roller bearing as its fulcrum, thereby causing a further depression of the pivoted 125 end of said bearing —13'— and corresponding arm of the bell-crank lever —13—.

130 The side of the guide —11— facing an approaching train is provided with a stop shoulder —11'— in the path of movement

of the lower weighted end of the lever-plunger —10—, but normally spaced a slight distance therefrom to allow a limited rocking movement of said lever-plunger by the flange 5 of the car-wheel, and then when the weighted end of said lever-plunger engages the shoulder —11—, the continued action of the flange on the car-wheel will depress the same for effecting the operation of the sign-
10 nal.

It will be noted, however, that this lever-plunger is free to swing in the opposite direction when encountered by the wheel of a train moving in that direction without effecting the operation of the bell-crank lever 15 —13—.

The other arm of the bell-crank lever —13— is pivotally connected to one end of a horizontal rod —17— which extends 20 transversely of the track through a protective pipe or casing —18— beneath the surface of the ground and some distance to the outside of the track where its opposite end is connected to a horizontally swinging bell-
25 crank lever —19— fulcrumed within a separate housing —20— and also beneath the surface of the ground.

The other arm of the bell-crank lever —19— is pivotally connected to one end of a rod —21— which extends horizontally 30 along the outside of the track beneath the surface of the ground and through a protective casing —22— into the hollow base of the corresponding signal tower —1— where it is pivotally connected to one of a 35 pair of horizontal rock arms —23— and —23'— projecting laterally from opposite sides of the same hub —24— which is journaled within said tower base.

40 The mechanisms for transmitting motion from each of the primary signal-setting devices —13— to the hub of the rock arms —23— and —23'— are identical, except that they are arranged in reverse order, 45 that is, the bell crank —19— at the approach opposite that shown in Fig. 7 is connected by a rod —21'— to the crank arm —23'— on the hub —24— and it, therefore, follows that when the hub —24— is rocked by the 50 depression of one of the wheel-operated members —10—, the other member —10— at the opposite approach of the roadway will be simultaneously depressed, partially under its own weight, assisted by the rocking 55 of its bell-crank lever —13—, but even if it should not be so depressed, it would simply be rocked by the flange of the car-wheel against the action of its counter-weight without in any way modifying the 60 action of its bell-crank lever or parts connected thereto.

On the other hand, it is equally evident that if the train approaches from the opposite direction named, it will produce the 65 same rocking motion of the hub —24— and

arms —23— and —23'—, as previously described, through the medium of the connecting rod —21—.

These actions are utilized to operate the semaphores in the following manner,—that 70 is, the hub —24— is provided with an additional crank arm —25— which is pivotally connected to a rod —26— having one end connected to a similar crank arm —27— on one side of an upright hub —28—. 75

This hub —28— is fulcrumed within the base of the tower —1— and, like the hub —24—, is provided with opposite radially projecting arms —29— and —29'— which are connected by links —30— and —30'— 80 to the lower arms of a pair of upright toggles —31— and —31'—, respectively.

The lower arms of these toggles are pivot- 85 ed to suitable supports in the base of the tower, while their upper arms are pivotally connected to corresponding arms of separate bell-crank levers —32— and —32'— which are journaled co-axially upon the same shaft —33—.

The other arms of said bell-crank levers 90 —32— and —32'— are pivotally connected to separate upwardly extending rods —34— and —34'— having their upper ends connected, respectively, to crank arms —35— and —35'— on the hubs of the semaphore 95 blades —2'— and —2—, respectively.

The toggle joints of the toggles —31— and —31'— are provided with stop plates 100 —36— for limiting their movement in the direction necessary to set their correspond- 105 ing signals, said toggle joints being arranged to automatically lock their respective arms and corresponding signals in their set positions, so that the one which is set will remain in such position until restored by an automatic restoring mechanism which will now be described.

Restoring mechanism.

As best illustrated in Figs. 7, 8 and 9, this 110 restoring device comprises a lever-plunger —37— which is very similar to the primary signal-setting lever —10—, in that its upper end is normally disposed in close proximity to the inner side of one of the rails, pref- 115 erably that opposite the one near which the levers —10— are located, and is adapted to be engaged by the flange of the foremost car-wheel which had previously operated one of the levers —10— to set the one sema- 120 phone and restore the other.

The lower end of this lever —37— is guided in an upright way —38— and is weighted to restore the lever to its upright position, the intermediate portion of said 125 lever being fulcrumed on a pivotal pin —39— having one end pivotally connected to one arm of a bell-crank lever —40— and its other end provided with a roller bearing —41— movable in a vertical slot 42. 130

This lever is adapted to be rocked and depressed by a car-wheel moving in either direction, and for this purpose both sides of the guide-way —38— are provided with 5 shoulders —43— in the path of movement of opposite edges of the lower weighted end of the lever —37—, so that after the car-wheel has rocked the lever in one direction or the other a limited distance, the continued pressure of the flange of said wheel 10 will force the lever downwardly along the slot —42—, thereby depressing the adjacent arm of the bell-crank lever —40—, it being understood that the connections between the stud or pin —39—, lever —37— and adjacent arm of the bell-crank lever —40— are 15 substantially the same as that described for the primary signal-setting lever —10—.

The other arm of the bell-crank lever 20 —40— is connected to a groove collar —44— which is loosely mounted on a rod —26'— forming a continuation of the rod —26—, previously described.

The collar —44— is normally held against 25 a stop —45— on the rod —26'— by means of a coil spring —46— surrounding said rod and having one end bearing against the adjacent end of the collar —44— and its other end engaged with a stop collar —47— also 30 on the rod —26'—.

The primary restoring lever —37—, together with the pin —39— and bell-crank lever —40— are mounted upon and within a housing —48— which is also embedded in 35 the ground beneath the surface thereof, and preferably between the rails of the track, and is connected to the bases of both of the signal towers —1— by pipe casings —49— leading from opposite sides thereof.

The rod —26'— extends through these casings and into their respective towers, each containing signals and operating mechanism therefor similar to those previously described, said rod —26'— serving as a 40 means for transmitting motion from the setting and restoring mechanism of one tower to the corresponding mechanisms of the other tower.

As previously intimated, the distance 45 between each primary actuator —10— for the signal-setting devices and primary signal-restoring actuator —37— is intended to be greater than the maximum length of any single train passing along the track, but in case a train should be of sufficient length to span such distance, then the action of the wheels of the rear cars upon one of the actuators —10— would tend to hold the primary restoring actuator in its uppermost position 50 in the path of travel of the flanges of the wheels of the forward cars, and it, therefore, follows that if the bell-crank lever —40— of the restoring mechanism was rigidly connected to the rod —26'—, the depression of the actuator —37— by the car-wheels would

in all probability break or bend one or more of the acting parts between said actuators and would also tend to vibrate the acting semaphore, and it is for this reason that the spring —46— is provided between one 55 arm of the bell-crank lever —40— and rod —26'— which allows the primary restoring actuator —37— and said bell-crank lever to vibrate under the action of the wheels of the car without affecting the operation of the 60 rod —26'— or any of the connections between said rod and the primary actuators, it being understood that the spring —46— is of sufficient tension to transmit motion from the bell-crank lever —40— to the rod 65 —26'— in restoring the signal-operating mechanisms to their normal positions.

In operation, assuming that a train is approaching the crossing from the right-hand end of Fig. 1, and that the semaphore signals 70 are in their normal positions for a clear track or with the safety signal "Go" registering with the sight openings —4— and the danger signals down or concealed within the towers; then, as the flange of the first approaching 75 car-wheel strikes the primary signal actuator —10—, the latter will be driven forwardly and downwardly, thereby drawing the rod —21— in the direction indicated by arrow —m—, Figs. 2 and 7, through the 80 medium of the transverse rod —17— and bell-crank lever —19—.

This movement of the rod —21— will rock the levers —23—, —23'— and —25— in the direction indicated by arrow *n*, Fig. 7, 85 which, in turn, will shift the rod —26'— in the direction indicated by arrow —o—, to rock the levers —27—, —29— and —29'— in the direction indicated by arrow —S—, Fig. 7, thereby forcing the toggle —31— to 90 its locked position for setting the danger signal —2'— and restoring the safety signal —2— and incidentally depressing the other primary signal-setting lever —10— at the opposite approach through the medium of 95 its connections with the crank arm —23'—.

The primary restoring actuator —37— is 100 normally depressed, but as soon as the rod —26'— is shifted in the manner just described, said actuator is elevated to bring 105 its upper end into the path of travel of the flanges of the car-wheels.

By automatically locking one of the toggles,—that is, by shifting its joint slightly 110 beyond a direct line between the pivots at opposite ends of its arms, the semaphores and their operating mechanism together with the primary restoring actuator —37— are locked in their adjusted positions, but as soon as the foremost car-wheel encounters 115 the primary restoring actuator —37—, the latter will be depressed, thereby shifting the rod —26'— in the opposite direction to flex 120 the previously locked toggle and restore the corresponding danger signal —2'— to its 125 130

normal position, and at the same time forcing the other toggle to its locked position to set the safety signal —2—, during which 5 operation the setting mechanisms for the danger signal will be restored and the primary restoring actuator returned to its normal position.

In like manner, a car approaching from the right-hand of the crossing, Fig. 1, will 10 first operate the adjacent primary setting actuator —10— to effect the same movement of the setting mechanisms for the danger signal and restoration of the safety signal, as previously described.

15. What we claim is:

1. In an automatic signal for railway crossings, the combination with a track, a signal tower and a signal on the tower, of car-operated means for setting the signal, 20 including an automatic device for locking the signal setting means in its set position, and car-operated restoring means for the setting means, including a yielding member, to allow the operation of said restoring means 25 while the setting means is locked.

2. In an automatic signal for railway crossings, the combination with a track, a signal tower at one side of the track near the crossing and a signal on the tower, of car-operated means for setting the signal, and additional car-operated means for restoring the signal and its setting means to their normal positions, said restoring means including a spring to allow it to be operated 35 while the setting means is still held by the car.

3. In an automatic signal for railway crossings, the combination with a track, a signal tower and a danger signal thereon, of 40 a primary signal actuator arranged in proximity to one of the rails some distance from the crossing, to be operated by the car-wheel of an approaching car, means for transmitting motion from said actuator to the signal 45 to set the same, said means including a self-locking toggle for holding the signal and its actuating means in their adjusted positions, and car-operated means near the crossing for breaking the toggle lock and restoring said signal and its operating mechanism 50 to their normal positions, said restoring means being spring-connected to the setting means to allow the restoring means to be operated independently of the setting means.

55. 4. In a signaling apparatus for railway crossings, the combination with a track, a signal tower near the crossing and a danger signal mounted on the tower, of a car-actuated member distant from the crossing, 60 means for transmitting motion from said member to the signal for setting the same, including a device for automatically locking the signal and its setting means in their set positions, a separate car-operated member 65 near the crossing, and means actuated there-

by for unlocking said device and restoring the signal and its setting means to their normal positions, and including a spring connection with the first-named means for permitting the operation of the second-named 70 member while the first-named member is still held in its set position.

5. In a signaling device for railway crossings, the combination with a track and a signal tower near the crossing, of distinctive 75 danger and safety signals pivotally mounted coaxially on the tower, the safety signal being normally exposed and the danger signal normally concealed, car-operated means for simultaneously rocking said signals in reverse directions for setting one signal and 80 restoring the other signal, and additional car-operated means for reversing the operation of the first-named means to restore the previously set signal and to set the other 85 signal.

6. In a signaling apparatus for railway crossings, the combination with a track, a signal tower near the crossing, and a danger signal mounted on the tower, of car-operated 90 means including a self-locking toggle for setting the signal and holding it in its set position, a car-operated member near the crossing, and means actuated by said member for flexing the toggle and restoring the 95 signal and its setting means to their normal positions, and including a spring connected to the setting means to permit the operation of the restoring means independently of the setting means.

7. In a signaling apparatus for railway crossings, the combination with a track and a tower near the crossing, of a danger signal mounted on the tower, car-operated means for setting the signal, a separate car-operated member near the crossing, and yielding connections between said member and the signal setting means for restoring the signal and its setting means to their normal positions when said member is actuated by the 105 car, the yielding connections serving to permit the operation of said member in case it should be engaged by the car while the signal and its setting mechanism are in their set positions.

8. In a signaling device for railway crossings, the combination of a hollow tower, a danger signal and a safety signal, both pivotally mounted coaxially within the upper portion of the tower, car-operated means for 120 rocking said signals simultaneously in reverse directions, and additional car-operated means for restoring the first-named operating means and signals to their normal positions.

9. In a signaling apparatus for railway crossings, the combination of a tower, a danger signal and a safety signal, both pivotally mounted coaxially within and upon the upper portion of the tower and normally 130

- held so that the safety signal is exposed to view and the danger signal is concealed within the tower, car-operated means for simultaneously rocking said signals in reverse directions to set the danger signal and conceal the safety signal, said means including separate devices for automatically locking the signals in their set positions, and additional car-operated means yieldingly connected to the first-named means for restoring the signals and their operating means to their normal positions.
10. In a signaling apparatus for railway crossings, the combination of a hollow tower having an offset portion at its upper end extending lengthwise of the track and provided with a sight-opening in one of its upright sides, a danger signal and a safety signal, both pivotally mounted coaxially within the upper portion of the tower and movable alternately into and out of said offset portion, the safety signal normally projecting into said offset portion and the danger signal normally extending into the upper portion of the tower, car-operated means for simultaneously rocking said signals in reverse directions from their normal positions so that the danger signal will assume a position within the offset and the safety signal will assume a position within the upright portion of the tower, said means including separate devices for automatically locking the signals in their set positions, and additional car-operated means for restoring the first-named means and signals operated thereby to their normal positions.

11. In a signaling apparatus for railway crossings, the combination of a hollow tower having an offset portion at its upper end extending lengthwise of the track and provided with a sight-opening in one of its upright sides, a danger signal and a safety signal, both pivotally mounted within the upper portion of the tower and movable alternately into and out of said offset portion, the safety signal normally projecting into said offset portion and the danger signal normally extending into the upright portion of the tower, car-operated means for simultaneously rocking said signals in reverse directions from their normal positions so that the danger signal will assume a position within the offset and the safety signal will assume a position within the upright portion of the tower, said means including separate devices for automatically locking the signals in their set positions, and additional car-operated means yieldingly connected to the first-named means for restoring said first-named means and signals to their normal positions and permitting the restoring means to be operated by the car while the first-named means and signals are in their set positions.

In witness whereof we have hereunto set our hands this 18th day of December, 1916.

FREDRICK D. McGINLEY.
